UNITED STATES PATENT OFFICE.

JOSEPH FALCK, OF CHICAGO, ILLINOIS, ASSIGNOR TO F. H. HILL COMPANY, OF CHICAGO, ILLINOIS, A CORPORATION OF ILLINOIS.

DESIGN FOR A BURIAL CASKET.

Application filed March 1, 1924. Serial No. No. 8,793. Term of patent 14 years.

To all whom it may concern:

Be it known that I, JOSEPH FALCK, a citizen of the United States, residing at Chicago, in the county of Cook and State of Illinois, have invented a new, original, and ornamental Design for Burial Casket, of which the following is a specification, reference being had to the accompanying drawing, forming a part thereof, wherein a burial casket is represented embodying the design.

I claim:

The ornamental design for a burial casket, as shown.

JOSEPH FALCK.
